Primary Examiner — Cynthia R Underwood(74) *Attorney, Agent, or Firm* — Collard & Roe, P.C.**CLAIM**

The ornamental design for pliers, as shown and described.

DESCRIPTION

FIG. 1 is a front and right side perspective view of pliers, showing my new design;

FIG. 2 is a right side view thereof;

FIG. 3 is a front view thereof;

FIG. 4 is a left side view thereof;

FIG. 5 is a rear view thereof;

FIG. 6 is an enlarged view of circle 6 of FIG. 1;

FIG. 7 is an enlarged view of circle 7 of FIG. 3; and,

FIG. 8 is an enlarged view of the head portion in FIG. 1 in an open position.

The features shown in broken lines depict portions of the pliers that form no part of the claimed design. The dash-dot straight lines delimit the boundaries of the claimed portions of the pliers and themselves form no part of the claimed design.
